UNITED STATES PATENT OFFICE.

UTLEY WEDGE, OF ARDMORE, PENNSYLVANIA.

FURNACE AND ALLIED STRUCTURE.

1,159,141.

Specification of Letters Patent.

Patented Nov. 2, 1915.

Application filed March 4, 1914. Serial No. 822,346.

To all whom it may concern:

Be it known that I, UTLEY WEDGE, a citizen of the United States, residing in Ardmore, Pennsylvania, have invented certain 5 Improvements in Furnaces and Allied Structures, of which the following is a specification.

My present invention is a modification of that forming the subject of my application 10 for Letters Patent filed February 11th, 1914, Serial No. 818,049, the main purposes of my present invention being to relieve the parts above the furnace or allied structure from the weight of the rotating annular hearth 15 and rabble carrying structure and its load, to insure steady movement of said structure, and to minimize the strain upon the same.

In the accompanying drawings—Figure 1 is a view, partly in side elevation and partly 20 in section, of one half of a furnace constructed in accordance with my invention; Fig. 2 is a top or plan view of one quarter of the furnace; Fig. 3 is a side elevation, on a larger scale than Fig. 1, of one of the sections 25 of the rotating annular hearth and rabble carrier and of the supporting and driving mechanism therefor, and Fig. 4 is a plan view of one section of the furnace illustrating a modified means for supporting 30 and driving the rotating annular hearth and rabble carrier.

The furnace has fixed annular walls 1 and 2 of such relative diameter as to contain between them a furnace chamber 3 of the desired capacity, this furnace chamber containing a series of superposed annular hearths, some of which (represented at 4 in the drawing) are fixedly mounted in the walls 1 and 2 and either project inwardly 35 from the outer wall 1 or outwardly from the inner wall 2, while others (indicated at 5 in the drawing) alternate with and lap said hearths 4, these hearths 5 being mounted upon a rotatable, annular drum, shell, or 40 other structure 6 which occupies a central position in the furnace chamber, and is connected to the arms of a spider 7 which thus serves to brace and stiffen the annular structure 6 and prevent distortion or malformation 45 of the same in the operation of the furnace. The spider 7 is free to turn about an axis which is concentric with the annular structure of the furnace, as shown in Fig. 2.

The fixed and rotating annular hearths 55 are intended to be provided on their under sides with rabbles for stirring and feeding

the ore or other material on the hearth beneath, but in order to prevent confusion, the illustration of these rabbles has been omitted.

The annular structure 6 is composed of 60 sections and in the furnace shown in Figs. 1, 2 and 3 each of these sections is provided with a pair of trucks 8 disposed beneath the same and each having bearings for the axles of a pair of wheels 9 which run upon an annular rail 10 mounted upon the base or floor of the furnace chamber, and thus serve to support the annular structure 6 and its load, and relieve the spider 7 from the performance of this duty. While the rotation 65 of the structure 6 may, as in the furnace of my former application, be effected by rotating the spider 7, I prefer to effect such rotation independently of the spider, and thus relieve the latter also from the driving 70 strain. In order to effect this result the wheels of either or both of the trucks 8 may have rotative movement imparted to them so as to travel along the rail 10 and carry the structure 6 with them. In the furnace 75 shown in the drawing I have illustrated the application of power to the wheels of only one of the trucks, the axle of each wheel having fixedly mounted upon it a chain wheel 11 which receives a drive chain 12 running therefrom to a chain wheel 13 carried by a shaft 14, mounted so as to be free to turn in suitable bearings on the spider 7 and rotated through the medium of any appropriate 80 train of gearing from an electric or other motor 15 mounted upon a plate 16, or other support, carried by said spider 7.

By applying driving power to each section of the rotating annular structure 6, steady movement of the same is insured, the strains are distributed throughout the structure, and the power units are of moderate size, and, by supporting the rotating annular structure from below, the weight of the same 95 and of its load are removed from the spider 7 and the latter can be of simpler and lighter construction than when the rotating annular structure is suspended from it, as in the furnace of my former application.

The advantage of using small power units 100 and applying the driving power to the rotating annular structure at different points throughout the same can, however, be attained in furnaces in which said rotating annular structure is not supported from below. For instance, in Fig. 4 I have shown 110 one section of a furnace in which the shaft

14 has fixedly mounted at its outer end a wheel 20 running upon a track 21 on the outer wall 1, a wheel 22, mounted so as to rotate freely on the shaft 14, running upon 5 a rail 23 on the inner wall 2, both wheels thus serving to support a section of the structure 6 and the wheel 20 also serving to rotate the same.

While the motive power for each truck 10 might be mounted upon the same, it is preferable to mount the motor and the primary members of the gearing above the furnace where they will be easily accessible and away from the hot and dusty conditions likely to 15 prevail at the bottom of the furnace.

The trucks, wheels and gearing located at the bottom of the furnace may, as shown by dotted lines in Fig. 1, be protected from the heat and dust by means of a shield or cover 20 of some material which is a non-conductor or a poor conductor of heat.

I claim:

1. The combination, in a furnace, of inner and outer fixed annular structures, the inner having annular hearths projecting outwardly therefrom and the outer having annular hearths projecting inwardly therefrom, and an intermediate rotating annular structure supported from below and 25 having annular hearths projecting in both directions therefrom, the inwardly projecting hearths lapping those of the inner fixed structure and the outwardly projecting hearths lapping those of the outer fixed 30 structure.

2. The combination, in a furnace, of inner and outer fixed annular structures, each having a series of superposed annular hearths projecting therefrom, those of the inner structure projecting outwardly and those of the outer structure projecting inwardly, and an interposed rotating annular structure supported from below and having on each side of the same a superposed 40 series of annular projecting hearths those on the inner side lapping corresponding hearths of the inner fixed structure and those on the outer side lapping corresponding hearths of the outer fixed structure.

3. The combination, in a furnace, of a fixed annular structure having an annular hearth projecting therefrom, a rotating annular structure supported from below and having an annular hearth projecting therefrom in a direction the reverse of that of the fixed annular structure and overlapping said fixed hearth, a rotating structure located above said hearth carrying structures and having an axial pivot, driving mechanism mounted upon said upper structure, and means whereby power is transmitted from said driving mechanism to the supporting devices for the rotating annular hearth carrying structure.

4. The combination, in a furnace, of a

fixed annular structure having a series of superposed annular hearths projecting therefrom, a rotating annular structure supported from below and having a series of superposed annular hearths projecting therefrom in a direction the reverse of those of the fixed annular hearths so as to overlap the latter, a rotating structure disposed above said hearth carrying structures and having an axial pivot, driving mechanism mounted upon said upper structure, and gearing for connecting said driving mechanism to the supporting devices for the rotating annular hearth carrying structure.

5. The combination, in a furnace, of inner and outer fixed annular structures, the inner having annular hearths projecting outwardly therefrom and the outer having annular hearths projecting inwardly therefrom an intermediate rotating annular structure supported from below and having annular hearths projecting in both directions therefrom, the inwardly projecting hearths lapping those of the inner fixed structure and the outer projecting hearths lapping those of the outer fixed structure, and means carried by said rotating annular structure for rotating the same.

6. The combination, in a furnace, of inner and outer fixed annular structures, each having a series of superposed annular hearths projecting therefrom, those of the inner structure projecting outwardly and those of the outer structure projecting inwardly, an interposed rotating annular structure supported from below and having on each side of the same a superposed series of annular projecting hearths those on the inner side lapping corresponding hearths of the inner fixed structure and those on the outer side lapping corresponding hearths of the outer fixed structure, and means carried by said rotating annular structure for rotating the same.

7. The combination, in a furnace, of a fixed annular structure having annular hearths projecting therefrom, a rotating annular structure having annular hearths projecting therefrom and lapping those of the fixed structure, a wheeled support for said rotating annular structure located below the same, and means located above the furnace for driving said wheeled support.

8. The combination, in a furnace, of fixed and rotating annular structures each having annular hearths projecting therefrom, those of one structure lapping those of the other, and said rotating structure being composed of a series of sections, a wheeled support upon which each of said sections is mounted, and means for rotating the wheels of each of said supports independently of those of the other sections.

9. The combination, in a furnace, of fixed and rotating annular structures each hav-

ing annular hearths projecting therefrom, those of one structure lapping those of the other, the rotating annular structure being composed of a series of sections, and independent driving devices for each of said sections.

10. The combination, in a furnace, of fixed and rotating annular structures each having annular hearths projecting therefrom, those of one structure lapping those of the other, the rotating annular structure being composed of a series of sections, and independent supporting and driving devices for each of said sections.

15. 11. The combination, in a furnace, of fixed and rotating annular structures, annular hearths projecting from each of said structures, the hearths of one structure lapping those of the other, a spider for bracing

and stiffening said rotating annular structure, and means for supporting said structure independently of the spider. 20

12. The combination, in a furnace, of fixed and rotating annular structures, annular hearths projecting from said structures, and those of one hearth lapping those of the other, a spider for bracing and stiffening said rotating annular structure, and means for supporting and rotating said structure independently of the spider. 25 30

In testimony whereof, I have signed my name to this specification, in the presence of two subscribing witnesses.

UTLEY WEDGE.
